UNITED STATES PATENT OFFICE.

ANTONIO BONGIOVANNI, OF BARNESBORO, PENNSYLVANIA, ASSIGNOR OF ONE-HALF
TO RONALD T. WHALEN, OF BARNESBORO, PENNSYLVANIA.

GLOBE SUPPORT.

Application filed August 16, 1921. Serial No. 492,691.

To all whom it may concern:

Be it known that I, ANTONIO BONGIOVANNI, a citizen of the United States, residing at Barnesboro, in the county of Cambria and State of Pennsylvania, have invented new and useful Improvements in 5 Globe Supports, of which the following is a specification.

This invention relates to globe supporting 10 means, the principal object of the invention being to provide means for detachably supporting a globe, such as the globes for electric lamps, gas lamps and oil lamps, in such a manner that the globe can be easily and 15 quickly removed and replaced.

Another object of the invention is to provide means for detachably connecting the support to the lamp or the lamp support.

This invention also consists in certain 20 other features of construction and in the combination and arrangement of the several views, to be hereinafter fully described, illustrated in the accompanying drawings and specifically pointed out in the appended 25 claim.

In describing my invention in detail, reference will be had to the accompanying drawings wherein like characters denote like or corresponding parts throughout the 30 several views, and in which:—

Figure 1 is a plan view of the invention.

Figure 2 is a longitudinal sectional view.

Figure 3 is a bottom plan view partly in section.

As shown in these views the device 35 consists of a body 1 which is of substantially inverted saucer shape and having a circular opening 2 at the center. The body is provided with a semi-circular reduced extension 3 which extends half-way around the opening and a semi-circular jaw member 4 is hinged to the extension 3, as at 5. Both the jaw and the extension are provided with handle parts 6 and a spring 7 is located between the handle parts and tends to hold the jaw member against the extension so that said jaw member and extension form a circular part the inner walls of which form continuations of the wall of the opening 2. Ears 8 are struck from the side edges of the saucer-shaped member and these ears are bent over the bights 9 of the substantially U-shaped springs 10 which are arranged within the body or member 1. Two 55 of these springs are used and the end of

each spring is bent outwardly to provide the handle parts 11 which extend through slots 12 formed in the sides of the member 1. These springs and their handles are so arranged that by pressing the handle 60 members of each pair towards each other the springs will be expanded so as to permit a globe to be placed between them and when the handle members are released the springs will contract and grip the globe and thus 65 hold same in the body.

By pressing upon the handles 6 of the jaw member and the extension the jaw member will be opened so that the device can be placed on a part of a lamp or its support and then by releasing the handles the spring 7 will cause the jaw 4 to close and thus grip the lamp or its support. 70

It is thought from the foregoing description that the advantages and novel features 75 of my invention will be readily apparent.

I desire it to be understood that I may make changes in the construction and in the combination and arrangement of the several parts, provided that such changes fall within 80 the scope of the appended claim.

What I claim is:—

A globe support of the character described comprising a substantially inverted saucer-shaped body portion provided with 85 slots on diametrically opposite sides and an opening in its center, ears formed on said body portion and designed to oppose each other, a pair of substantially U-shaped springs arranged one above the other in the 90 body portion, a bight formed on said springs intermediate of the ends and adapted to secure said springs to the body portion through the medium of the ears, a handle formed on each end of each spring 95 and designed to project through the slots for easy manipulation thereof, a semi-circular reduced extension formed on the body portion, and extending half way around the opening therein, a jaw member 100 pivotally secured to the extension and normally arranged around the other half of the opening in the body portion, a handle formed on the jaw and semi-circular extension respectively and a spring bearing 105 against the respective handle for the purpose specified.

In testimony whereof I affix my signature.

ANTONIO BONGIOVANNI.
